UNITED STATES PATENT OFFICE.

MARCELLE J. HARDING, OF NEW YORK, N. Y.

TOILET-ACCESSORY CONTAINER.

1,246,541.

Specification of Letters Patent.

Patented July 13, 1920.

Application filed July 5, 1919. Serial No. 303,695.

To all whom it may concern:

Be it known that I, MARCELLE J. HARDING residing at New York, county of New York, and State of New York, have invented certain new and useful Improvements in Toilet-Accessory Containers, of which the following is a specification.

This invention relates to improvements in containers or cases for toilet articles as used by men and has as its principal object the provision of a compartmented case, preferably made of metal, adapted to compactly contain a number of articles needed in the performance of a man's toilet, the several articles being closely packed in small compass readily carried.

This and other like objects are attained by the novel construction and combination of parts hereinafter described and shown in the accompanying drawings, forming an important part of this specification, and in which:—

Figure 1 is a top plan view of a case filled with toilet articles, the cover being shown in an open or raised position, and

Fig. 2 is a perspective view of the container when emptied of its contents.

The case or container consists of a rectangular metallic box having a bottom 10 from which rise imperforate side walls 11 and 12, respectively at the rear and front, joined by end walls 14 and 15, the same being of double construction so as to present a ledge 16 around the entire structure.

A hinge 18, of the piano box type connects a cover 19 having extending edges 20 adapted to partially envelop the top of the case and rest upon the ledge 16.

Adjacent to the end 14 is a compartment 22 formed by a transverse partition wall 23 extending partially across the interior and joined by an end wall 24; extending longitudinally within the casing are two other partition walls 25 and 26, while from the latter extends a short transverse partition wall 27, notches 28 being formed in the wall 26 so as to permit the fingers to readily engage with articles in the compartments, respectively 30 and 31 at the front, the same being adapted to contain a small cake or bar of soap 50, and a package of talcum powder 51.

The center longitudinal compartment 32 is suited to receive a shaving brush 52 having a hollow handle 53 in which may be

contained soap-powder, a styptic pencil or other like articles, the same being secured in place by the screw cap 54.

The rear longitudinal compartment 33 is adapted to hold a collapsible tube 55 containing tooth paste. A plug 56, forming the handle of the razor is at the end of the tube, while beyond and below is positioned a tooth brush 58, a comb 59 being placed between the back of the tooth brush and the rear wall 11 of the case.

In the end compartment 22 is contained the safety razor frame or body 60 and a package of razor blades 61. Engaged to the inner side of the cover 19 is a mirror 64 preferably of highly polished metal provided with a single perforation 65 by which it may be suspended from a nail or like projection at any convenient point so as to be used in performing toilet operations such as shaving, dressing the hair, etc., etc.

In order to provide for proper ventilation and air circulation throughout the case, so that the implements, if placed therein in a moist or wet condition may dry, a plurality of perforations 36 are formed in the end wall 14, adjacent to the tooth brush 58 similar perforations 37 and 38 being formed in the wall 15 adjacent to the end of the shaving brush 52 and soap 50 respectively.

From the foregoing it will be seen that a neat and serviceable toilet case has been disclosed particularly adapted for soldiers and travelers and that the same forms a useful adjunct to the kit or luggage carried by such persons whereby they are enabled to perform their toilet in a convenient manner.

It will be noted that the transverse wall 23 projects rearwardly beyond the longitudinal partition 25, thus forming in the compartment 33 a projection or shoulder which will act as a stop to hold in place, or at least restrict in its longitudinal movement, a nail file 60 which, together with a pair of tweezers 61, is located at the front of the widened right-hand portion of said compartment 33.

When the lid or cover 19 is down, it engages the upper edges of the walls or partitions 23, 24, 25, 26 and 27, and thus practically shuts off each of the compartments of the box from its neighbors, except that the compartments 30 and 31 communicate with the compartment 32, by means of the 110

notches 28. Air entering through the openings 36 practically reaches only the tooth-brush compartment 33. On the other hand, a circulation of air is possible through the compartment 31 and 32 containing soap and the shaving brush respectively, the air entering say through the opening 37 into the compartment 32, then passing through the right-hand notch 28 into the compartment 31, and out through the openings 38. The compartment 30, containing talcum powder, receives some air from the compartment 32, through the left-hand notch 28. The compartment 22, containing the body of the razor and the razor blades, has no communication with the outside air when the box is closed. Thus the several compartments differ as to their connection with the outside air, the most abundant air supply being provided for the compartments 31 and 32, in which are placed the articles likely to be in the wettest condition.

Having thus described my invention, and set forth the manner of its construction and

use, what I claim as new and desire to secure 25 by Letters Patent, is:—

As a new article of manufacture, a box body having a plurality of partitions dividing it into compartments, the said partitions extending upwardly to the same 30 level, and a cover adapted to engage the upper edges of said partitions when it is down, sundry of said compartments communicating with each other when the cover is down, through openings in the respective partitions, and the wall of the body having openings leading to two of said communicating compartments, whereby a circulation of outside air may be effected through said communicating compartments, the wall of the 40 body being further provided with an opening leading to one of the other compartments, and being imperforate where it bounds still another compartment.

In testimony whereof I have affixed my 45 signature.

MARCELLE J. HARDING.
